PAPERMAKING

Donald B. Bradner and George C. Munro, Hamilton, Ohio, assignors to The Champion Paper and Fibre Company, Hamilton, Ohio, a corporation of Ohio

Application March 1, 1939, Serial No. 259,154

6 Claims. (CL 92—75)

This invention relates to paper making and has particular reference to apparatus for controlling the gloss-producing operations performed on the paper in accordance with the gloss characteristics of finished paper issuing from the calenders in a manner to give a gloss of hitherto unattainable uniformity to the finished paper web.

One of the most important properties of paper is its gloss, and more particularly the uniformity of the degree of gloss it possesses. The gloss characteristic is indicative to a great degree, not only of the appearance and feel of the paper, but also of the surface smoothness, density, and other of the properties which determine the printing quality thereof. Thus, if the manufacture of paper is controlled to give a uniform degree of gloss, greatly enhanced uniformity of these other properties is also secured and the finished paper is of exceptional value to the printer because of the more uniform and dependable printing results which are possible thereon.

Gloss is produced by passing coated or uncoated paper between pressure rolls in a calender. The degree of gloss imparted to the paper by the calender may be varied within limits by increasing or decreasing the pressure exerted by the rolls on the paper. However, the gloss characteristic does not remain constant with constant calender pressure. Variations in moisture content, in composition, density, and other properties of the stock and the coating, all change the gloss characteristic produced by a given calender pressure. Because all of these properties are seldom uniform throughout any considerable area in paper as commonly made, corresponding variations in gloss are imparted to different portions of a paper web even though a constant value of calender pressure is maintained.

It has been the practice in paper making to regulate the gloss imparted to paper by periodically taking samples from the paper web issuing from the calender, visually comparing the gloss thereon with that on standard samples, and adjusting the calender pressure in an effort to correct gloss variations. Such samples are frequently not typical of all the paper in the roll. The accuracy of such visual comparisons depends largely on the skill of the operator and is necessarily subject to wide variation. Further, the taking and examination of samples usually involves stopping the paper web, which slows down production. If the comparison is made without stopping the web, the time necessarily consumed

in taking the sample and making comparison permits a considerable length of paper web to pass through the calender before a corrective adjustment can be made. The difficulties and disadvantages inherent in the method of controlling the gloss by sampling and making visual comparisons are more serious the higher the paper speeds, and have become more important with the modern demand for greater speeds and higher quality. For the reasons described it is almost impossible to produce by methods heretofore known, paper having a satisfactorily uniform degree of gloss.

It is the primary object of the present invention to provide apparatus for continuously producing finished paper having a substantially uniform gloss. More specifically, the invention contemplates apparatus for producing a continuous web of paper having a gloss characteristic which does not vary beyond predetermined and controllable limits, and for effecting such production without the interruptions to operation required in taking samples for visual comparison. To this end, the apparatus of the invention provides a substantially continuous control of the calender pressure and in some cases the surface dryness of the paper being calendered which corrects deviations of gloss from the desired degree as soon and as often as such deviations occur, and not only avoids the wide variations in gloss inherent in prior practices, but prevents changes in gloss which could not even be detected by the customary visual inspection.

A further object of the invention is the provision of means substantially continuously responsive to variations in gloss on the finished paper acting to simultaneously regulate the pressure applied to the paper at both ends of the calender rolls, while at the same time, providing independent manual control of the adjustment of the pressure applied to the paper at opposite ends of the rolls. This feature permits an initial adjustment of the difference in pressure exerted by the rolls on opposite side portions of the paper web, which pressure difference is maintained while the values of absolute pressure on both sides of the web are simultaneously varied in accordance with changes in the gloss characteristic.

In general, the objects of the invention are carried out by variably adjusting the pressure exerted on the paper, and in some cases the dampness of the surface of paper in the calender in response to and in accordance with all significant changes in the gloss characteristic.

of the paper issuing therefrom. This is preferably accomplished by continuously specularly reflecting a beam of light from the finished surface of the moving paper web issuing from the calender and varying the pressure applied to the calender rolls by means responsive to changes in the intensity of the reflected light beam. In accordance with a modification of the invention, the corrective capacity of the apparatus is increased by altering the surface moisture of the paper web entering the calender in response to gloss variations when adjustment of calender pressure is insufficient to produce the required correction, and the change in surface moisture may comprise the primary corrective adjustment rather than the change in calender pressure, if desired.

The only gloss producing factors that are variably controlled in accordance with the present invention are the calender pressure and the surface moisture of the paper passing through the calender. Accordingly, the term "gloss producing capacity" is used in the appended claims to define the capacity of either the calender pressure or the surface moisture of the paper entering the calender or both of these factors to affect the degree of gloss produced on the paper surface, and this term does not include the capacity of other factors to affect such degree of gloss.

In describing the invention in detail, reference will be made to the accompanying drawings, in which certain embodiments thereof have been illustrated. In the drawings:

Figure 1 is a diagrammatic and simplified representation of one form of apparatus for carrying out the invention, embodying a paper calender in which the roll pressure is hydraulically applied and adjusted;

Figure 2 is a sectional view of the calender illustrated taken on line 2-2 of Figure 1;

Figure 3 is a wiring diagram of the apparatus illustrated in Figure 1;

Figure 4 is a diagrammatic and simplified view of a part of a paper calender illustrating the controlled addition of moisture to the paper web; and

Figure 5 is a wiring diagram, similar to Fig. 3, showing an arrangement adapted to operate surface moisture supply adjusting means only when pressure adjustment is inadequate to give the desired degree of correction.

Referring to Figures 1 and 2, the calender comprises the usual stack of rolls 11 which may be of metal or of metal alternating with compressed paper, cotton, or other suitable material, mounted in a framework 12. The calender illustrated may be either a "machine calender" at the end of a paper making machine or a "super-calender" separate from a paper making machine. The rolls 11 all rest upon the lowest roll which is journaled in the frame 12 and is driven by a suitable source of power in a known manner. A paper web 13 enters the calender at the top, passes between the successive pairs of rolls and leaves at the bottom in the usual manner, passing over a truly running fly roll or equivalent means 14. In order to increase the pressure exerted upon the paper beyond that imposed by the weight of the rolls themselves, blocks 15 are provided over the journals of the top roll 11, and pressure is applied to these blocks through rods 16 by pistons 17 which operate in hydraulic cylinders 18 and 19. Hydraulic pressure in the cylinders 18 and 19 is provided by fluid supplied through pipes 21 and 22 leading separately to

the two cylinders 18 and 19 which apply pressure to the opposite ends of the rolls. The pressure on each end of the rolls is separately controlled by separate valves 23 and 24 which receive fluid from a high pressure supply 25 and supply it to the respective cylinders 19 and 18, at controlled pressure through pipes 21 and 22. This may be accomplished by various pressure regulating means such, for example, as that shown in a copending application of George C. Munro, entitled "Hydraulic calender," Serial No. 259,156, filed concurrently herewith. Pressure regulating apparatus of the type there disclosed has been diagrammatically represented herein. The apparatus is so constructed that when the shafts 41 and 42 of the valves 23 and 24 are rotated in one direction or the other, the pressure applied from the supply 25 to the calender pressure cylinders 18 and 19 is increased or decreased, the change in pressure being proportional to the amount of rotation of the valve shafts. The shafts 41 and 42 of the valves 23 and 24 are rotated by the gears 27 and 28 respectively, and the gears are driven in unison to give equal simultaneous variation to the pressure on opposite ends of the calender rolls, by the gears 29 and 30 mounted on shaft 31 which is rotated in either direction desired by gear 32 mounted on the shaft of a reversible motor 33 which is operated as more fully hereinafter described.

If it is desired to vary the pressure on one end of the roll with respect to that on the other end, this is accomplished by manually pressing knob 34 and throwing gear 29 out of mesh with gear 27. Gears 28 and 30 and shaft 31 then remain stationary while gear 27 is being rotated to adjust valve 23. As soon as pressure on knob 34 is released gear 29 is returned into mesh with gear 27 by spring 35. Further operation of motor 33 then adjusts the pressure on both ends of the calender rolls simultaneously, maintaining the pressure differential as set.

The pressure on both ends of the rolls may be quickly thrown on or off as desired, without changing the adjustment by throwing valve lever 36 to the "on" or "off" position as indicated in Figure 1.

For the guidance of the operator, pressure gauges 37 and 38 may be provided, advantageously connected to the pipes 21 and 22 through pressure snubbers 39 and 40, which may be in the form of small orifices, and which protect the gauges against sudden pressure changes.

Means are provided for continuously detecting the gloss characteristic of the paper web issuing from the calender, and controlling the calender pressure in response to changes in the gloss characteristic. It has been found that this can be accomplished by directing a beam of light from a source of constant intensity on to the finished paper web surface, and variably controlling the calender pressure by means responsive to the amount of light from such beam which is specularly reflected from the paper web surface. The means provided for detecting the intensity of the reflected light preferably comprises a photoelectric cell or cells, and the arrangement is preferably such that the controlling light is reflected from an area which extends for a considerable distance transversely of the moving paper web. Excellent results are obtained by the use of light directing and detecting apparatus and paper web supporting means of the type disclosed in our copending

application Serial No. 259,155 entitled "Gloss meter" and filed concurrently herewith, now Patent No. 2,246,501, granted June 24, 1941. Apparatus of this type has been illustrated in Figure 1 in a diagrammatic and simplifier manner. This apparatus, which is mounted on a support 58 attached to calender frames 12, will not be described in detail herein since a full description and explanation thereof appears in our said copending application.

A beam of light is directed onto the paper web from a light source 51 which is advantageously in the form of an incandescent lamp constituting a high intensity source of light of small area. The lamp 51 is supplied with current from a line *s*; *t* energized by a constant voltage regulator or other known means of maintaining constant voltage, not shown, through an autotransformer or a variable resistance 52 which can be used to adjust the intensity of the light for reasons hereinafter pointed out. A voltmeter 53 may be wired in parallel with the lamp 51 to indicate the applied voltage for the convenience of the operator.

In order that the intensity of the light 51 may be maintained at a constant value in accordance with the adjustment, a photoelectric cell 55 is mounted adjacent the light. The output of this cell is measured on a microammeter 56. In order that the operator may readily detect variations from the correct value of light intensity, a variable resistance 57 is placed in parallel with the meter and used to bring it to a standard reading advantageously at the center of the scale after the light intensity has been adjusted to the correct value as hereinafter described. Any variations which may occur in the intensity of light source 51, due to aging of the lamp or other cause, will be immediately made apparent by a departure of the microammeter 56 from the standard reading. The operator can then restore the light intensity to its proper value by adjustment of the resistance 52.

The paper web is suitably supported at the point of detection in such a manner that its reflective surface is held in a fixed and definite position regardless of the speed of travel of the web. This may be accomplished by passing the web under tension over a fly roll 14. The light from the lamp 51 is concentrated and directed by suitable means into a beam which strikes the paper web along a path of considerable length extending transversely of the web. The light from this beam, which is reflected by the paper surface, passes through a tubular shield 58 and falls on a photoelectric cell 59 which is connected by wires *k* and *l* to the meter and photoelectric relay box designated as a whole by the numeral 60. The relay box 60 is connected by wires *b*, *i* and *j* to a control panel designated as a whole by the numeral 110, which panel in turn is connected by wires *i* and *j* to a control box 100 which serves to control motor 33 and which is advantageously energized from a three phase power line *a*, *g*, *h*. The panel 110 is also energized by leads *a* and *h* from the said three phase circuit, for purposes hereinafter described.

The manner in which these devices function to cause operation of motor 33 to increase the calender pressure when the gloss is below a predetermined lower limit and to decrease the calender pressure when the gloss is above a predetermined upper limit will be understood by reference to Figure 3. In this figure broken lines 68, 100 and 110 enclose those elements which

are included in the panels and boxes designated 68, 100 and 110 in Figure 1, except that to simplify the diagram switch 121 is shown in Figure 3 within the limits of panel 110 whereas it is actually located outside this box in connection with valve handle 36 as indicated in Figure 1.

Reference will first be made to the circuit for measuring the current output of the photoelectric cell 59, which current is a measure of the gloss on the paper leaving the calender. This photo-cell, as pointed out in our copending "Gloss meter" application, may be of any desired type, but is advantageously of the "blocking layer" type in which the output depends upon the light falling on the cell, but which does not require the addition of potential from an outside source. For example, a cell of the type described in United States Patent No. 2,034,334, has been found suitable for this purpose. The output of this cell may be measured by any suitable device, but this is advantageously accomplished by some type of potentiometer circuit. A simple type of potentiometer is shown, for purposes of illustration, but it will be understood by those skilled in the art that other special or modified types of circuit may be used if desired. In the circuit illustrated in Figure 3, a resistance 61 is placed across the terminals of the cell 59. A variable resistance 64 serves to regulate current from battery 65 in the circuit including resistance 64 and slide wire 68. The instrument is standardized by connecting standard cell 62 in the circuit by moving switch 63 to the right in Figure 3, setting slider 67 on slide wire 68 at a point which corresponds to the potential of the standard cell, and then adjusting resistance 64 until the galvanometer 66 reads zero. After the instrument is standardized switch 63 is moved to the left in Figure 3, thus connecting photocell 59 in the circuit in place of standard cell 62. If the slider 67 is left in the same position the galvanometer 66 will read zero when the potential maintained by photocell 59 across the resistance 61 is equal to the potential of standard cell 62. The values of resistance in the potentiometer circuit, the constants of the photoelectric cell 59, the scale of the slide wire rheostat 68 and the intensity of the light source 51 are all so chosen and adjusted that the position of the slider 67 at which the galvanometer 66 is not deflected in either direction, directly indicates the degree of gloss on the paper as defined by the intensity of light reflected from the paper at high angles of incidence as described in our copending "Gloss meter" application, and advantageously measured in units corresponding to those in which gloss is measured and specified to the calender department. Any deviation in the value of the gloss on the paper passing over roll 14, from that represented by the setting of slider 67 on slide wire 68 will therefore result in an electric current through galvanometer 66. This current and the resulting deflection of the galvanometer from its zero position illustrated in Fig. 3 correspond in magnitude and direction to the magnitude and direction of the gloss deviation.

In a preferred embodiment of our invention, 66 is a mirror galvanometer whose mirror is illuminated by a light 70 through a suitable lens 71. When the galvanometer is undeflected, the reflected light beam takes the position shown in Figure 3. A plane glass plate 72 is interposed in the path of the reflected light beam. This plate reflects a part of the beam onto a screen 73 which is visible to the operator (see also

250-201

4

2,312,310

Figure 1.) When the galvanometer is undeflected, the reflected beam falls on a clear space in the center of this screen. When the galvanometer reading changes in either direction, the light beam shifts to the right or left on this screen. A shift greater than a predetermined amount throws the beam through a band of one color 73—H on the one side, indicating too high a degree of gloss, or a band of another color 73—L on the other side, indicating too low a 10 degree of gloss.

The means by which the detected changes in gloss variably adjust the calender pressure will now be described. The part of the light beam from galvanometer 66 which passes through glass plate 72 strikes a photoelectric cell 74 whenever it travels to a degree which indicates that the gloss is above a predetermined upper limit, and strikes a photoelectric cell 75 whenever it travels in the other direction to a degree which indicates that the gloss is below a predetermined lower limit.

When the gloss is too high and this light beam consequently falls on photoelectric cell 74 it acts through an amplifier 76 to operate relay 77 which as hereinafter described closes a circuit to cause the valve operating motor 33 to rotate in a direction to decrease the calender pressure. When the gloss is too low and the light beam consequently falls on photoelectric cell 75 it acts through an amplifier 78 to operate relay 79 which, similarly, closes a circuit to cause the motor 33 to rotate in a direction to increase the calender pressure. In the arrangement illustrated in Figure 3, the position of the photoelectric cells or of screens adapted to shield them from the light beam, are preferably made adjustable as for example, by means of adjusting screws 74—A and 75—A, so that the neutral zone, or range of permissible variation, between them may be adjusted to any width required to give the desired closeness of control. The upper limit of gloss above which the light beam falls on cell 74 and causes a reduction in calender pressure, and the lower limit of gloss below which the light beam falls on cell 75 and causes an increase in calender pressure, are not the limits of tolerance within which the gloss of the finished paper is to be held, but are somewhat closer to the set value of gloss, so that the light beam, falling on cell 74 or 75 has opportunity to correct the deviation from the set value before it becomes great enough to be objectionable. Thus the term "permissible range" as used in this specification and the appended claims means the range of gloss variation within which the corrective mechanism does not function, and should be clearly distinguished from the considerably broader range of gloss variation which is permitted on acceptable paper.

The limits of galvanometer deflection are so fixed that the light beam cannot travel beyond the outer limits of cells 74 and 75. This means that however great the deviation from standard gloss, the controls will always function to correct it unless intentionally turned off.

Although normally the devices as described function to maintain a uniform gloss on the paper being produced, within predetermined limits, it is possible for the operator to disconnect the control means by means of a switch 120 as hereinafter described, or, while leaving the control means operative, to release the calender pressure by turning valve handle 36 to the "off" position. This is frequently done by the opera-

tors to facilitate operation when starting, stopping, in the vicinity of splices, etc., and results in the production of a section of paper web having an excessively low gloss at these times. Unless extreme care is used, some of this low gloss paper may be included with the good paper delivered to the customer. In order to prevent this, an additional photoelectric cell 81 may be located so that as soon as the gloss falls below a predetermined value, lower than that at which light falls on cell 75 to close relay 79, light falls on cell 81 which acts through an amplifier 82 and coil 83 to operate a marking device 84 (see also Figures 1 and 2). The device 84 unmistakably and conspicuously marks all paper of unacceptably low gloss, which is then readily discovered and removed before delivery of the finished paper. In cases in which the functioning of the gloss responsive control mechanism is prevented in the manner described, a decrease in gloss from the correct value causes a galvanometer deflection which increases from zero so that the light beam first falls on cell 75 and then reaches cell 81 when the gloss reaches a predetermined low limit. The cell 81 or a screen adapted to shield part of the cell from the light beam is preferably adjustable, as for example, by an adjusting screw 81—A, to permit adjustment of the low limit of gloss. It should be noted that the illustration in Figure 3 is purely diagrammatic and cell 81 is shown in a position to indicate the relative deflections required to cause the light to fall on cells 75 and 81. In practice, the cell 81 is so disposed that light can fall on both of the cells 75 and 81 simultaneously. If desired, another photoelectric cell can be used to cause the paper to be marked wherever the gloss is above a predetermined upper limit. There is however, relatively little danger of this defect and in most cases, the marking of low gloss paper is all that is required.

Further reference to Figure 3 will show how the previously described relays 77 and 79 function to control the energization and direction of rotation of the pressure control motor 33. The motor 33 is connected to a power source, advantageously a three phase alternating current line, designated a. g. h. in the drawings (see also Figure 1) through the reversing switches 101 and 102, operated by electromagnetic coils 103 and 104 respectively. An interlock shown diagrammatically at 105 prevents the closing of either switch when the other is closed.

The adjustment of the calender pressure in accordance with changes in gloss is made operative by throwing the control switch 120 (see also Figure 1) to the "on" position. Switch 121, which is operated by the valve handle 36 (as indicated diagrammatically in Figure 1) which throws the hydraulic pressure on or off, then serves to direct the current through green lamp 122 (which indicates that both switch 120 and switch 121 are "on" so that gloss responsive control will function) or through red lamp 123 which indicates that gloss responsive control will not function. An interrupter switch 125 which must also be closed in order that the gloss responsive control may function will be hereinafter fully described and may for the present be considered to be closed.

Assuming that switches 120 and 121 are in the "on" position and the degree of gloss is too low, the light beam reflected from the galvanometer mirror strikes photoelectric cell 75 and thereby causes the closing of relay 79. Under these con-

ditions current from line wire *h* passes through switch 120, wire *c*, and switch 121 to junction 126. From this point, it passes through green light 122, which indicates that the gloss responsive control is in operation, to line wire *a*. From junction 126, current also passes through wire *b*, and interrupter switch 125 (here assumed to be closed), closed contacts of relay 79, wire *j*, coil 103, wire *e* and closed high limit switches 112 and 113 (the operation of which will be hereinafter described) to line wire *a*. This energization of coil 103 closes switch 101 and thus causes the motor 33 to rotate in a direction to effect an increase in the calender pressure. If the degree of gloss is too high, the light beam reflected from the galvanometer mirror strikes photoelectric cell 14 and thereby closes relay 11. In this case, green light 122 remains lighted, and current from junction 126 flows through wire *b* and interrupter switch 125, closed contacts of relay 77, wire *i*, coil 104, wire *f*, and low limit switches 115 and 116 (normally closed as hereinafter described) to line wire *a*. This energization of coil 104 closes switch 102 and causes the motor 33 to rotate in a direction to effect a decrease in calender pressure.

Means may also be provided for adjusting the calender roll pressure manually, and such means is illustrated in Figure 3 as push button switches 111 and 114, also shown on the control panel 110 in Figure 1. These manually operable switches are respectively connected to energize the coils 103 and 104 of the motor energizing switches 101 and 102, through circuits clearly shown in Figure 3. The motor switch operating coil energizing circuits of the bush button switches 111 and 114 respectively include the high limit switches 112, 113, and the low limit switches 115, 116. All of these limit switches are normally closed, and are opened under certain circumstances, as explained below.

Overadjustment of either of the valves 23 and 24 in either direction might damage the mechanism as described in said copending application entitled "Hydraulic calender" and as diagrammatically indicated in Figure 1, where it appears that the valve adjusting shafts 41 and 42 are threaded to cause adjusting nuts 43 and 44 to travel away from each other to increase the calender pressure. In order to prevent such damage high limit switches 113 and 112 are arranged, as diagrammatically indicated in Figure 1, to be opened by the nuts 43 and 44 respectively reaching the upper limit of their respective adjustments. As shown in Figure 3, the opening of either or both of these switches will break the circuit through relay 79 or push button 111 and thereby deenergize coil 103 and permit switch 101 to open and stop operation of motor 33 and upward adjustment of valves 23 and 24. In order to prevent damage by overadjustment of nuts 43 and 44 towards each other to decrease the calender pressure, low limit switches 115 and 116 are similarly arranged to be opened by the nuts 43 and 44 respectively reaching the lower limits of their respective adjustments. Similarly the opening of either or both of these switches will break the circuit through relay 77 or push button 114 and thereby deenergize coil 104 and permit switch 102 to open and stop operation of motor 33 and downward adjustment of valves 23 and 24. These limit switches may advantageously be adjustably mounted on valves 23 and 24 by known means, not shown, so that it is possible to set any desired limits on the possible pressure adjustment, in case narrower limits than imposed by the

valve structure should be desired to protect the calender, or for any other reason.

The apparatus described above serves to increase the calender pressure and thereby to increase the gloss being imparted to the paper when this gloss is too low, and to decrease the calender pressure and thereby to decrease the gloss being imparted to the paper when this gloss is too high, and will leave the calender pressure unchanged when the gloss is between predetermined limits. The full change of calender pressure is not reflected as a change of gloss on the paper passing over roll 14 (Figure 1) until that part of the paper web which was just entering the first calender nip when the pressure change was completed has passed through the calender and onto roll 14. Accordingly, an appreciable time interval elapses during which the gloss on the issuing paper web at roll 14 remains too low regardless of an adequate increase in calender pressure, or too high regardless of an adequate decrease in calender pressure. During this time the change in pressure would continue whether or not further change in that direction were required. To prevent the phenomenon known as "hunting" it is necessary that the pressure change during this time shall not be so great as to carry the gloss across the neutral zone or permissible range and thus make an adjustment in the opposite direction necessary as soon as the full effect of the adjustment is registered on the glossmeter.

This can be accomplished by establishing a suitable relation between the speed of adjustment and the speed of the paper through the calender, so that the time required for the paper to pass from the first nip of the calender to the glossmeter over roll 14 is less than the time required for the adjusting mechanism to change the gloss through the neutral zone, or permissible range. For this purpose, an adequate speed reduction between motor 33 and valves 23 and 24 may be used, or the valves may be operated rapidly, to secure a prompt corrective change in gloss, and this rapid operation periodically interrupted for time intervals of such predetermined frequency and duration that the gloss responsive devices will have opportunity to stop further pressure change before the adjustment has been carried entirely across the neutral zone, and adjustment in the opposite direction is required. The paper speeds on which these speeds or time intervals are based are advantageously the normal or operating speeds of the calender and not the slow "threading in" speeds sometimes used.

This periodic interruption may be accomplished by a switch 125 which is advantageously of a sealed mercury type and may advantageously be operated by a cam 127 driven by a clockwork 128, which may be driven by a spring or a synchronous clock motor, through the medium of cam follower 129 to which the switch 125 is attached as indicated diagrammatically in Figure 3. The time "on" and "off" and the entire cycle are advantageously adjustable so they may be regulated in conformity with the speed of paper travel and the distance through the machine to the glossmeter.

From the foregoing description it is apparent that the calender pressure may be increased or decreased manually (by push buttons 111 and 114) regardless of whether or not the pressure valve handle 36 and therewith switch 121 are "on" or "off" and regardless of whether the gloss responsive control switch 120 is "on" or "off" except that with the control switch on and the

6250-201

2,312,310

motor 33 running under control of the gloss responsive devices, interlock 105 will prevent manual control from stopping or reversing the direction of its operation until its operation is stopped by the opening of switch 125 or by a change of gloss acting through the gloss responsive control pressure on either side of the calender stack without undue interference with the gloss responsive control system. With the switch 120 "off" and pressure switch 121 "on," it is possible to operate entirely with manual control if desired.

While operating with the control switch 120 "on" it is possible by means of valve control handle 36 to release the pressure for threading or other purpose, thus throwing the green light off and red light on and disconnecting gloss responsive control. When the pressure is again thrown "on," gloss responsive control is resumed with the pressure unchanged from its previous value, the variations in gloss which may have occurred during the threading, etc., due to the release of pressure or other cause, having been unable to effect the operation of motor 33 while switch 121 is in the "off" position due to throwing the valve control handle 36 to the "off" position.

The mode of operation will now be described. Assume it is required to produce paper having gloss of a specified value. The gloss responsive mechanism is first calibrated by taking a standard sample having a known value of gloss (defined as hereinbefore described), wrapping this sample around roll 14 (Figures 1 and 2), setting the slider 67 on slide wire 68 by means of knob 69 to the known gloss value of the standard sample, then adjusting resistance 52 to vary the intensity of light source 51 until the line of light on screen 73 is in the center of the clear space between the two colored areas. In order to facilitate the detection of slight variations in light intensity from the standard value so determined, the rheostat 51 (see Figure 1) is adjusted until microammeter 56 indicates a selected even value, advantageously at the center of the scale, for the output of cell 55. During the subsequent operation of the device, any departure of the microammeter reading from this standard value is immediately corrected by readjusting rheostat 52 to correct the intensity of light source 51. If the gloss on the calibration sheet used is different from that required on the paper to be calendered, the slider 67 is moved by turning knob 69 until the scale of the slide wire 68 indicates the required gloss value.

Control switch 120 is then turned to the "on" position, the paper is threaded through the calender in the usual manner, operation is started, and the pressure valve handle 36 is moved to the "on" position, which applies the pressure to the calender and throws switch 121 to the "on" position, extinguishes the red light 123 and lights the green light 122, indicating that the gloss responsive control is functioning. If the gloss, at the start, is much too low, galvanometer 66 will deflect to throw the light beam onto a colored part 73-L of screen 73 and onto photoelectric cells 75 and 81. Light on the latter will cause marker 84 to deface the sheet to show that it is to be rejected. At the same time, cell 75 will cause the closing of relay 79 which acts as described to close switch 101 and operate motor 33 intermittently under control of interrupter switch 125 to increase the calender pressure and consequently the gloss on the paper.

As soon as the gloss on the paper reaches an acceptable value, the galvanometer deflection de-

creases so that light no longer falls on cell 81, marker 84 is released and the paper is no longer marked for rejection. In the meantime, motor 33 continues to increase the pressure until galvanometer 66 no longer reflects light onto cell 75, but between cells 74 and 75. Relay 79 is then released, switch 101 opens, and motor 33 stops, the pressure having reached the correct adjustment. The line of light is then in the clear space in the center of screen 73, indicating a correct value of gloss. If now the characteristics of the paper entering the calender change so that it is harder to finish, the light moves onto one of the colored areas 73-L on screen 73, light again falls on cell 75 and the adjustment described is repeated. If on the other hand the characteristics of the paper change in the other direction so that the gloss becomes higher, light falls on area 73-H and on cell 74. This immediately closes relay 71 which acts as described to close switch 102 which operates motor 33 in a direction to decrease the calender pressure and prevent too great a gloss from being imparted to the paper.

In case of a splice or "tear out," etc., in the paper which, in the operator's opinion, may cause a break if run through the calender at full speed and pressure, he first reduces the speed, and the control mechanism alters the pressure if necessary to maintain the proper degree of gloss. Before the splice or other defect enters the calender, the operator usually throws valve handle 36 to the "off" position which removes pressure from the calender and throws switch 121 to the "off" position extinguishing green light 122 and lighting red light 123 which indicates that the gloss responsive control is out of operation. The removal of the pressure soon results in a decreased gloss which causes deflection of galvanometer 66 to throw the light beam first onto cell 75 which closes relay 79, but because switch 121 is open, coil 103 is not energized and switch 101 is not closed so that no change is made in the pressure adjustment. Light reflected by galvanometer 66 also falls on cell 81 causing the paper to be marked as below standard until the splice or other defect has passed through and gloss responsive control restored by throwing valve lever 36 and consequently switch 121 back to the "on" position. This restores the pressure to its last adjusted value which, unless the raw stock characteristics have changed, will be the value required to impart the correct degree of gloss to the paper.

In case the characteristics of the paper entering the calender change to a great degree, for example, if the stock becomes so hard that it will not take the required gloss with the maximum pressure available, the pressure setting of the valves 23 and 24 is raised in the manner just described until at least one of these valves reaches the upper limit of its adjustment. When this occurs the corresponding adjusting nut 43 or 44 contacts and opens corresponding high limit switch 113 or 112 as hereinbefore described thus preventing further operation of motor 33 in a direction to increase the pressure. In such a case the gloss will be too low and will be so marked by marker 84 as described unless prevented by means such as hereinafter described. If, on the other hand, the lightest pressure available causes too high a gloss, one of limit switches 115 or 116 will be opened by contact with the corresponding adjusting nut 41 or 42 and will serve in the same manner to stop operation of motor 33, and prevent further adjustment which might damage

the mechanism. The operator can then usually correct this condition of excessive gloss by threading the paper through fewer nips in the calender.

With most grades of paper, the changes in pressure provided by the gloss responsive means of the invention constitute a very accurate and adequate control of the gloss. That is to say, the gloss responsive means used is able to detect and act upon much smaller differences in gloss than can be detected by the naked eye, and considerable changes in calender pressure are required in order to give relatively small changes in gloss. The mechanism of the invention is thus able to alter the pressure, as required to maintain the gloss well within the minimum visual requirements of uniformity.

At some times, due to unusual dryness of the paper or to other causes, such abnormally high calender pressures may be required to give the desired gloss to the paper that, if used, they would result in excessive wear and tear or other damage to the calender. The desired gloss can be secured under such circumstances by moistening the paper slightly before it enters the calender. Because, other things being equal, the more moist the paper surface, the higher will be the gloss imparted thereto by the calender, we find it advantageous to accomplish this moistening by a steam shower, or other moistening device, of known type connected with and controlled by the gloss responsive control means hereinbefore described.

Since it is only necessary to change the surface moisture to affect the gloss produced in the calender, the addition of moisture may take place immediately before the paper enters the calender and with this arrangement, the moisture may not have time to distribute itself throughout the thickness of the web prior to calendering.

In accordance with the present invention, this gloss responsive control of the application of moisture may be combined with the gloss responsive pressure control, hereinbefore described, to maintain a uniform standard value of gloss on the paper leaving the calender. This is advantageously accomplished by the electric circuits illustrated in Figures 1 and 3 by gearing a motor (designated at 333 in Figure 4, but which may be in this case the above described motor 33) both to a single steam valve mechanism 251 and to the duplex hydraulic valve mechanism 23-24. This modification is illustrated in Figure 4 which shows diagrammatically only the upper calender rolls 11 together with the entering paper web 13 below which is placed a steam shower 250 of known construction. The amount of moisture supplied to the paper through pipe 252 in the form of steam is controlled by valve 251. The opening of valve 251 is increased by the motor 333 when the gloss is too low, and decreased when the gloss is too high. This increase in the amount of steam applied to the paper takes place simultaneously with the increase in calender pressure hereinbefore described, and the decrease in steam applied takes place simultaneously with the decrease in calender pressure. A given amount of adjustment therefore has a greatly increased effect on the degree of gloss imparted to the paper so that the possible range of adjustment is greatly increased, though the sensitivity is decreased.

In place of a steam shower, known types of water sprays, similarly controlled, may be used in some cases though they are generally less satisfactory.

We can however, combine the moistening of

the paper with the pressure adjustment in such a manner as to enormously broaden the range of gloss responsive control without impairing the sensitivity of the control. To accomplish this, we provide mechanism which operates to effect changes in moisture content in response to changes in gloss characteristic only when gloss responsive changes in calender pressure are insufficient to correct the deviations in gloss from the required standard. This may be accomplished, as shown in the disclosed embodiment, by employing the gloss responsive calender pressure control mechanism hereinbefore described, and, in connection with the limit switches 112, 113, 115 and 116, providing valve motor controlling switches 312, 313, 315 and 316, as illustrated in Figure 5, so that when high limit switches 112 and 113 are opened, switches 312 and 313 respectively are closed, and when low limit switches 115 and 116 are opened switches 315 and 316 respectively are closed. This operation of switches 312, 313, 315, and 316 may be accomplished in the same manner as the operation of pressure control switches 112, 113, 115, and 116, as shown in Fig. 1, by means of the sliding nuts 43 and 44. The corresponding switches may be mounted side by side so as to be contacted by the respective adjusting nut at the limit of its motion at substantially the same time. As shown in the figure, the pressure control switches are normally closed and adapted to open when contacted by nut 43 or 44. The steam valve motor control switches 312, 313, 315, and 316, however, are normally open and adapted to be closed by contact with the nut 43 or 44. Since exact and dependable simultaneity of the closing of one of the switches 312, 313, 315, or 316, and the opening of its corresponding switch 112, 113, 115, or 116, may be difficult to secure and maintain in practical operation, and since when the pressure control switches open, the motion of the nuts 43 and 44 stops, it may be found desirable to set the steam control switches to close somewhat before the opening of the pressure control switches.

With this arrangement, the pressure control mechanism functions exactly as hereinbefore described until it is no longer sufficient to hold the gloss within the specified limits. When the pressure reaches its upper limit and still is not adequate to impart the requisite degree of gloss to the paper, at least one of the high limit switches 112 and 113 is automatically opened, as hereinbefore described, to prevent further operation of motor 33 in a direction to increase the pressure. At least one of the switches 312 and 313 is closed at the same time, or earlier if desired. As soon as one of these switches is closed, coil 303 is energized, closing switch 301, which operates motor 333 to increase the opening of steam valve 251 and thereby increase the amount of steam supplied to the paper web entering the calender. As soon as the increasing moisture content of the paper has produced a sufficiently increased gloss, the gloss responsive means closes relay 77 and functions to decrease the calender pressure as described, the low limit switches 115 and 116 being closed at this time. The adjustment of the valves 23 and 24 to accomplish this decrease in pressure serves to close the high limit switches 112 and 113 and open switches 312 and 313 thereby stopping the operation of motor 333 and the resulting increase in the supply of steam to the paper. This steam supply then remains constant until more steam is required to give the specified gloss to the paper, when the operation described

is repeated, or until in its gloss responsive downward adjustment the pressure reaches the lower limit fixed by the location of switches 115 and 116 on valves 23 and 24. When this occurs, at least one of the low limit switches 115, 116 opens and prevents further decrease in pressure. At least one of the switches 315, 316 has then been closed, energizing coil 304, thereby closing switch 302 which operates motor 333 in a direction to decrease the amount of steam supplied to the paper through valve 251. With this arrangement, the pressure control functions as before and with the same degree of sensitivity to maintain a constant gloss on the paper being produced, and a change in the amount of steam being applied only takes place when the range of pressure variation is insufficient to compensate for the variations in the paper coming to the calender.

It will be understood that our devices can be considerably varied in construction and application without departing from the present invention.

The potentiometer circuit illustrated and described, for measuring the output of the photoelectric cell responsive to the gloss, has been shown in a very simple form for purposes of illustration, and it will be readily understood that any desired refinements may be introduced without departing from the spirit of the present invention.

Although a potentiometer circuit is particularly advantageous for measuring the output of the photocell which is responsive to the gloss, other arrangements may be used for this purpose.

For example, a microammeter may be placed directly in the circuit with the photocell to measure its output. The indicating element is preferably a mirror which reflects the light beam from light 70 onto the photoelectric relays as above described and illustrated in Figure 3. With such an arrangement the microammeter will only be at zero when there is no light falling on the photoelectric cell 59. In order that the reflected light beam may be set in the center of the neutral zone between cells 74 and 75 and of the clear space on screen 73 at any desired value of gloss, the microammeter may be mounted on a concentric swivel with a calibrated scale reading in points of gloss just as does the scale 68 (Figures 1 and 3). Any deviation from the gloss value to which the microammeter has been turned will function exactly as in case of the potentiometer to adjust the calender pressure to correct the gloss value.

In place of the mirror galvanometer 66 or the microammeter just described, it is possible to use an instrument of any suitable known type with an indicating hand in place of the mirror, and mechanical relays in place of the photoelectric relays illustrated and described.

Our invention, as hereinbefore described, will maintain a constant uniform degree of gloss on paper. Gloss is not only one of the most important properties of paper, but the control of the manufacturing processes to give uniformity of gloss also serves to increase the uniformity of various other properties of paper, surface smoothness, density, etc., all of which go to make up the printing quality of paper. The use of our invention thus makes possible a greater uniformity of printing quality than has heretofore been available in commercial printing papers, with a corresponding increase in their value to the printer.

We claim:

1. Apparatus for producing paper having substantially uniform gloss which comprises in combination a calender, means including a motor for varying the gloss producing capacity of said calender, means including a photoelectric cell for detecting deviations from a predetermined value of the gloss on the paper as it passes from the calender, and an automatic electric relay circuit controller electrically connected to said photoelectric cell and to said motor to operate said motor in response to variations in the output of said photoelectric cell to increase the gloss producing capacity of the calender when the gloss on the paper falls below said predetermined value and to decrease the gloss producing capacity of the calender when the gloss on the paper exceeds said predetermined value.

2. Apparatus for producing paper having substantially uniform gloss which comprises in combination a calender, an adjustable pressure controlling device for varying the pressure in said calender, a motor for adjusting said pressure controlling device, means including a photoelectric cell for detecting deviations from a predetermined value of the gloss on the paper as it passes from the calender, and an automatic electric relay circuit controller electrically connected to said photoelectric cell and to said motor to operate said motor in response to variations in the output of said photoelectric cell to increase the pressure in the calender when the gloss on the paper falls below said predetermined value and to decrease the pressure in the calender when the gloss on the paper exceeds said predetermined value.

3. Apparatus for producing paper having substantially uniform gloss which comprises in combination a calender, means including a motor and a fluid control valve operated thereby for varying the surface moisture of the paper entering said calender, means including a photoelectric cell for detecting deviations from a predetermined value of the gloss on the paper as it passes from the calender, and an automatic electric relay circuit controller electrically connected to said photoelectric cell and to said motor to operate said motor in response to variations in the output of said photoelectric cell to increase the moisture on the surface of the paper entering the calender when the gloss on the paper falls below said predetermined value and to decrease the moisture on the surface of the paper entering the calender when the gloss on the paper exceeds said predetermined value.

4. Apparatus for producing paper having substantially uniform gloss which comprises in combination a calender, means including a motor for varying within predetermined limits the pressure applied to the paper by said calender, means including a second motor for varying the surface moisture of the paper entering said calender, means including a photoelectric cell for detecting deviations from a predetermined value of the gloss on the paper issuing from said calender, and a controller electrically connected to said photoelectric cell and to said motors to operate said first named motor in response to variations in the output of said photoelectric cell to increase the pressure applied to the paper by said calender when the gloss on the paper falls below said predetermined value and to decrease the pressure applied to the paper by said calender when the gloss on the paper increases above said predetermined value and to operate said second

named motor to increase the surface moisture of the paper entering said calender only when the gloss on the paper falls below said predetermined value and the pressure applied to said paper has reached its maximum limit and to decrease the surface moisture of the paper only when the gloss on the paper increases above said predetermined value and the pressure applied to the paper has reached its minimum limit.

5. Apparatus for producing paper having substantially uniform gloss, which comprises in combination a calender, an adjustable pressure controlling device, for varying the pressure in said calender, a motor for adjusting said pressure controlling device means and a fluid controlled valve operated thereby including a motor for varying the surface moisture of the web of paper entering the calender, means including a photoelectric cell for detecting deviations from a predetermined value of the gloss on the paper as it passes from the calender, and an automatic electric relay circuit controller electrically connected to said photoelectric cell and to said motors to operate said motors in response to variations in the output of said photoelectric cell and to so control the direction of operation of said motors that said first named motor will increase the calender pressure and said second named motor will increase the surface moisture of the paper web entering the calender when operated by said

controller in response to detection of gloss below said predetermined value, and said first named motor will decrease the calender pressure and said second named motor will decrease the surface moisture of the paper web entering the calender when operated by said controller in response to detection of gloss above said predetermined value.

6. Apparatus for producing paper having substantially uniform gloss comprising in combination a calender, means including a motor for varying the pressure in said calender, means for projecting a beam of light at an angle against the surface of the moving paper web issuing from the calender, a photoelectric cell in the path of light from said source that is specularly reflected from the surface of the moving paper web, and an automatic electric relay circuit controller electrically connected to said photoelectric cell and connected to govern the operation of said motor to cause said motor to increase the pressure in said calender when the intensity of said specularly reflected light is below a predetermined value and to cause said motor to decrease the pressure in said calender when the intensity of said specularly reflected light is above said predetermined value.
